US0D1086277S

(12) **United States Design Patent** (10) **Patent No.:** **US D1,086,277 S**
(45) **Date of Patent:** **** Jul. 29, 2025**

(54) **ELECTRONIC DEVICE**

(71) Applicant: **SpotOn Transact, LLC**, San Francisco, CA (US)

(72) Inventors: **Carol Marie Oles**, Baldwin, MD (US); **Doron Friedman**, Glencoe, IL (US); **Jeffrey Haller**, Redwood City, CA (US); **Zachary Alan Hyman**, Belvedere, CA (US); **Kenneth John North**, San Carlos, CA (US)

(73) Assignee: **SpotOn Transact, LLC**, San Francisco, CA (US)

(**) Term: **15 Years**

(21) Appl. No.: **29/922,610**

(22) Filed: **Dec. 22, 2023**

CLAIM

The ornamental design for an electronic device as shown and described.

DESCRIPTION

FIG. 1 is a perspective view of an electronic device showing our new design;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken lines shown in the Figures are for the purposes of illustrating portions of the electronic device which form no part of the claimed design.

1 Claim, 7 Drawing Sheets
